UNITED STATES PATENT OFFICE.

ABRAM NEWKIRK, OF CLEVELAND, OHIO.

FENCE.

SPECIFICATION forming part of Letters Patent No. 339,919, dated April 13, 1886.

Application filed July 22, 1885. Serial No. 172,301. (No model.)

To all whom it may concern:

Be it known that I, ABRAM NEWKIRK, of Cleveland, in the county of Cuyahoga and State of Ohio, have invented certain new and useful Improvements in Fences; and I do hereby declare the following to be a full, clear, and exact description of the invention, such as will enable others skilled in the art to which it pertains to make and use the same.

10 My invention relates to improvements in fences in which the rails of the respective adjacent panels are secured on opposite sides of the posts, each set of rails forming a panel being secured to the post by a wire that is first fastened to one end of the post and then brought around the outside of the rail and back behind a nail, and so on until each rail is secured, after which the wire is strained between each rail by means of a hook and lever and a nail driven 15 to hold the wire taut, to the end that by straining the wires the latter are embedded in the rails, so that the latter are held from drawing endwise out of the loops, and by means of the two sets of nails the wires are held in position 20 to prevent the rails from moving upward.

25 In the accompanying drawings, Figure 1 is a view in perspective of a portion of a fence embodying my invention. Figs. 2 and 4 are enlarged views in perspective of a portion of 30 a post and panel, showing the manner of attaching and straining the wires. Fig. 3 is a view in perspective of a suitable hook for engaging the wire in straining the latter.

A represents the posts, and *a b c d, &c.*, the 35 different rails or boards of the panels; B, the wires, and *c' and c''* the nails that secure the wires to the posts. The wire B is first secured at one end of the post, it matters not which end, but we will suppose at the bottom—that 40 is, at a suitable distance from the ground—to support the bottom rail or board. A nail, *b'*, is partly driven, and the wire is bent around the nail and the short end tucked under between the long portion of the wire and the post, 45 after which the nail is driven "home." (See top of post in Fig. 2.) The wire is then passed up outside of the rail or board *a* and carried behind a second nail, *c''*, that is at a suitable distance up along the post for supporting the 50 rail or board *b*. The wire is next carried outside of the rail *b*, and so on until all of the rails or boards of the panel are secured, when

the end of the wire is brought back over the top nail and secured in the same manner as at the bottom nail. At this stage of construction 55 the relation of parts is shown in Fig. 4. The rails, if secured in this manner, always can be raised more or less, according to the length of the loops of wire, the length of the latter being more or less, according to the distance of the 60 rails apart.

To prevent the rails from being raised, and to prevent the possibility of the rails being moved endwise and the fence drawing apart, I have devised the following: By means 65 of a suitable claw—for instance, the claw K—and a lever, K', the wire between each rail is strained or drawn inward with considerable force, so that the wire will cut into the edges of the board or rail. While the wire is thus 70 held taut a nail, *c'*, is driven in front of the wire and between the prongs of the claw K. (See Fig. 2.) By reason of the wire being strained in this manner and made to cut into the edges of the boards, the boards or rails are 75 securely held from moving endwise, and by reason of the nails *c'* and *c''*, respectively above, below, and between the boards or rails, said boards or rails cannot be raised in the loop, as would be the case if the wire were left as 80 shown in Fig. 4. When the wire is applied as shown in Fig. 4, it is drawn as tight as can conveniently be done by hand. The straining of the wire and securing it by the nail *c'* does not, therefore, require any extra wire. 85

It is evident that the action of the wind or the rubbing of cattle will not affect this fence so long as the posts are not broken, and the upheaval of any of the posts by the frost will not injure the boards or rails, but will only 90 cause the wires to be embedded deep in the rails, and if boards are used there will be no tendency to split or injure the same, as would be the case if the boards were nailed to the posts. It matters not how irregular the shape 95 of the posts or rails may be, the latter are held equally firm as if the posts and rails were of sawed timbers.

The fence is easily and cheaply made, and if it is desired to remove a panel it is easily 100 done by drawing the top nails, when the wires may be successively detached from the other nails. Panels can be taken out and put up with little trouble. Of course, when a frequent

passage-way is required, gates or "bars" are preferable; but every farmer knows that it is a great convenience to have a fence any panel of which, in case of emergency, may be removed and returned to its place with little trouble. If a rail is broken, by drawing the nail c^2 next above such rail the latter may be drawn out endwise and a new one inserted in its place, after which the loop should be again strained and another nail c^2 driven.

To prevent the posts from turning, I attach a loop, g , to the end of one rail of each panel and secure it to the post in the position shown in Fig. 1. This loop will counteract the strain of the fastening-wires on the opposite sides of the post, and prevent the post from turning while constructing or after the completion of the fence.

I am aware that it is not new to attach the

rails of a fence to the posts by passing a wire 20 in front of the rails and behind nails driven into the sides of the post between the rails. In this device, if the wires should be applied while under strain, the post would turn. By applying the loops g the tendency of the post 25 to turn is overcome.

What I claim is—

The combination, with the rails, posts, and wires B, arranged substantially as indicated, of the loop g , substantially as set forth. 30

In testimony whereof I sign this specification, in the presence of two witnesses, this 16th day of July, 1885.

ABRAM NEWKIRK.
